(57) **CLAIM**

The ornamental design for a pre-fabricated dome house, substantially as shown and described.

DESCRIPTION

FIG. 1 is a front elevational view of the pre-fabricated dome house, the opposite side being a mirror image, showing our new design;

FIG. 2 is a side view thereof, the opposite side view being identical; and,

FIG. 3 is a top view.

1 Claim, 3 Drawing Sheets

FIG. 1

FIG. 2

FIG. 3
